UNITED STATES PATENT OFFICE

2,518,555

JAR COVER LIFTER

Herbert E. Knight, Falmouth, Maine

Application July 12, 1946, Serial No. 683,087

2 Claims. (Cl. 81—3.42)

1

My present invention relates to a novel device for use, for example, in removing the cover from a jar.

In spite of attempts made to provide a device that will enable jar covers to be removed with less difficulty than is so commonly experienced, none has combined an inexpensive and rugged structure with ease of its adjustment and use.

In accordance with my invention, I provide a device consisting of a first member, the intermediate part of which is flat and which has at one end a first cover engaging element and at the other end a downturned flange through which is threaded an adjustable element. I form a second member with a curved portion terminating in a second cover engaging element, a flat portion, and a seat intermediate these portions disposed to be engaged by the adjustable element when the members are assembled. Preferably, the second member, except for its cover engaging element, has marginal stock disposed in the zone of the curved portion and the seat as an upstanding flange and in the zone of the flat portion to establish a slideway receiving the flat portion of the first member thereby to slidably interconnect the members so that as the adjustable element is threaded into engagement with the seat, the clamping elements are drawn towards each other. In practice, the flat and curved portions of the second member are so disposed relative to each other that when the two members are assembled, the intermediate part of my device is spaced from the cover of the jar to which it is fitted to enable it to be readily manually engaged with the folded marginal stock ensuring that a firm grip can be comfortably maintained.

In the accompanying drawings, I have shown an illustrative embodiment of my invention from which its novel features and advantages will be readily apparent.

In the drawings:

Fig. 1 is a top plan view of my device applied to remove the cover from a jar.

Fig. 2 shows the device of Fig. 1 in side view, and

Fig. 3 is a section along the lines 3—3 of Fig. 1.

At 5, I have indicated a jar having a cover 6 which, even when tightly seated thereon, may be readily removed by my jar opening device.

A device in accordance with my invention comprises first and second members generally indicated at 7 and 8 respectively. The first member 7 includes an intermediate flat portion 9 having a downturned flange 10 at one end and its other end shaped to establish a first cover engaging ele-

2

ment 11. The cover engaging element 11 is preferably in the form of a wedge having a centrally disposed notch 12. Threaded through the flange 11 is the adjusting element 13.

5 The second member 8 consists of a curved portion 14 terminating in a second cover engaging element 15 and a flat portion 16 separated from each other by the seat 17 adapted to be engaged by the adjusting element 13. In the embodiment 10 of my invention shown in the drawings, the curved portion 15 tapers inwardly towards the seat 17 so that the second cover engaging element 15 is of substantial size. Except for the element 15, the second member 8 has marginal stock which 15 in the zone of the curved portion 14 and the seat 17 is disposed upwardly as at 18 and in the zone of the flat portion 16 is disposed to establish a channel 19 slidably receiving the flat portion 9 of the first member 7 thereby to slidably 20 connect the first and second members so that by advancing the adjusting element 13 into engagement with the seat 17, the cover engaging elements 11 and 15 are drawn into clamping relation to the cover 6.

25 Preferably, the flat portion 16 is disposed relative to the curved portion 14 so that when assembled and clamped in position, the intermediate part of the device is spaced from the cover 6 so that it may be firmly grasped by the hand 30 of the user. When thus held, the marginal stock ensures that a firm grip may be comfortably maintained.

35 From the foregoing, it will be apparent that my invention provides a jar opening device of simple and inexpensive construction that is easily adjusted and operated to remove the cover from its jar.

What I therefore claim and desire to secure by Letters Patent is:

40 1. A device for use in removing the cover from a jar, said device comprising a first member including at one end a first cover engaging element and at its other end a downturned flange, an adjustable element threaded through said flange, 45 and a second member including at one end a slideway slidably connecting the intermediate portion of said first member thereto, a second cover engaging element at its other end, and an intermediate seat engageable by said threaded element as it is rotated to draw said clamping elements towards each other, the portion of said second member between said seat and said second element defining with said intermediate portion of said first member such an obtuse angle that the 50 intermediate part of said device is spaced suffi-

ciently above a cover engaged by said elements to establish said part as a hand grip.

2. A device for use in removing the cover from a jar, said device comprising a first member including a flat intermediate portion, a first cover engaging element at one end and a downturned flange at its other end, an adjustable element threaded through said flange, and a second member including a curved portion terminating in a second cover engaging element, a flat portion and an intermediate portion establishing a seat engageable by said adjustable element, both of said portions including marginal stock, the marginal flanges of said curved portion extending upwardly and the marginal stock of the flat 10

portion extending upwardly and inwardly to establish a slideway slidably receiving the flat intermediate portion of said first member thereto to interconnect said members.
